UNITED STATES PATENT OFFICE

E. LUSTER A. MORROW, OF SUNNYSIDE, WASHINGTON

ASSORTING TABLE DEFLECTING MEANS

Application filed June 4, 1926. Serial No. 113,685.

The invention relates to assorting tables particularly adapted for assorting fruits and vegetables, but applicable for general use, and particularly designed for assorting potatoes.

5 A further object is to provide the table partitions with rearwardly extending deflecting arms having link connections and adapted to be shifted laterally at the end of the table whereby potatoes will be discharged into spaced sacks carried by sack holders at the end of the table.

10 A further object is to provide hinged deflecting members above the discharge end of the conveyor and movable laterally over the conveyor, and a transverse supporting bar above the conveyor and arched by U-shaped members carried by the deflecting members for supporting the deflecting members and guiding the same as they are shifted laterally.

15 With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

20 In the drawings:—

25 Figure 1 is a side elevation of the assorting machine.

Figure 2 is a top plan view of the assorting machine.

30 Figure 3 is a vertical longitudinal sectional view through the assorting machine.

Figure 4 is a detail sectional view taken on line 4—4 of Figure 1.

35 Figure 5 is a detail perspective view of one of the bag holders and a portion of the assorting table.

Figure 6 is a perspective view of the hinged deflecting members.

40 Referring to the drawing, the numeral 1 designates the assorting table which is horizontally disposed and 2 the inclined and upwardly extending feeding conveyor as a whole.

The assorting table 1 comprises a frame 3, which frame comprises spaced side bars 4 and 5, and disposed in said frame is an end-

5 less conveyor 6 which extends over sprockets 7 carried by transversely disposed shafts 8 and 9 at the ends of the frame 3. Shaft 9 is preferably mounted in belt tighteners 10 whereby the endless conveyor 6 may be maintained at a proper tension. Endless conveyor 6 comprises sprocket chains 11 which extend over the sprockets 7 and transversely disposed spaced slats 12 on which potatoes are conveyed. The frame 3 is supported on legs 13, and it is to be understood that the frame may be formed from any material however it is preferably built up from metal angles and channels. Disposed above the endless conveyor 6 and adjacent the upper side bars 4 of the frame are longitudinally disposed partitions 14, which partitions at spaced points are provided with outwardly curved deflecting members 15, which extend outwardly to points adjacent the discharge openings 16 at 79 the inner ends of the bag holders 17, and it will be seen when bags 18 are placed in the bag holders 17 potatoes which may be picked from the main body thereof, which are being conveyed by the conveyor 6, and placed outside of the partitions 14 will be discharged into bags carried by the bag holders. Hingedly connected at 19 to the ends of the partitions 14 are rearwardly deflecting members 20, which members extend slightly beyond the end of the conveyor and are maintained in uniform spaced relation by means of a link connection 21, which is connected at 22 to the arms 23 of U-shaped members 24, and which U-shaped members arch the upper side of the supporting bar 25, which extends across the rear end of the assorting table. It will be noted the brackets 24 are carried by the deflecting members 20, and the supporting member 25 will support the same and form a guiding means during the shifting of the members 20 when they are moved to positions to discharge into either of the bag holding devices 17^a and bags carried thereby at the end of the table. A receptacle 26 may be placed on the floor or ground beneath the space between the bag holders 17^a, whereby any of the potatoes discharged from the end of the conveyor 6 during the shifting operation will be dis-

charged into the receptacle. The supporting bar 25 is provided with spring clips 27 which receive and grip the U-shaped members 24 according to the position of the deflecting members 20 and prevent displacement of the deflecting members 20 incident to the pressure on the inner sides thereof while deflecting potatoes into either sack carried by the sack holders 17^a.

The outer end of the shaft 8 is provided with a sprocket 28 and extending around said sprocket 28 and a sprocket 29 carried by the transversely disposed shaft 30 is a sprocket chain 31, and it will be seen when the shaft 30 is rotated through the medium of the belt 32 which moves in the direction of the arrow *a* and the pulley 33, the table conveyor 6 will be operated. The belt 32 extends forwardly and over a small pulley 34 rotatably mounted on a drive shaft 35, and which drive shaft is provided with a drive pulley 36, over which a belt 37 extends, and which belt may lead to any suitable source of power. Slidably keyed on the shaft 35 is a clutch member 38, which is adapted to be moved into and out of clutched relation with the pulley 34 through the medium of a lever 39 having an arm connection 40 with the slidable clutch member and against the action of the coiled spring 41, therefore it will be seen that the operator can control the operation of the device at all times. Although a power driving mechanism has been described, it is obvious any kind of power may be used or the conveyor 6 may be manually operated if desired.

The bag holders 17 at the sides of the table and 17^a at the end of the table comprise horizontally disposed U-shaped members 42, the arms of which are preferably hingedly connected at 43 to the vertical arms 44 of upwardly extending U-shaped members 45 carried by the sides of the assorting table, and which U-shaped members 42 are supported at their outer ends by means of upwardly extending chains 46 which connect their outer ends to the U-shaped members 45. The outer ends of the U-shaped members 42 are provided with downwardly and outwardly curved hooked prongs 47 which are adapted to pierce a bag and hold one side thereof. The inner side of the bag 18 is held by the curved prongs 48 of the arms 49 of a U-shaped member 50, and which arms are pivotally connected to the arms of the U-shaped member 42, and to the outer side thereof, and when moved downwardly into the plane of the U-shaped member 42 receives said U-shaped member therein, and the upper end of the bag is gripped by said member. The U-shaped member 42 is provided with an outwardly extending arm 51 which is received between the arms 52 of the handle members 53 of the U-shaped member 50, and after which the slidable rectangular shaped mem-

ber 54 is moved inwardly to the positions shown in Figure 2 where it will cooperate with the arm 51 and maintain the U-shaped members 42 and 50 in the same plane and hold the bag. The discharge openings 16 are provided with downwardly extending plates 55 which are designed to extend into the bags 18 for deflecting potatoes into the bags and under which plates the inner sides of the bags are disposed.

The feeding conveyor 2 comprises side bars 56 which incline downwardly and forwardly and are supported by the arms 57 and by the upper ends of the supporting legs 13. Disposed within the feeding conveyor 2 is an endless conveyor 58, which conveyor extends over sprockets 59 carried by the transversely disposed shafts 60 and 61, and the conveyor is driven through the medium of the sprocket 62 carried by one end of the shaft 60 and the sprocket 63 over which the sprocket chain 64 extends, therefore it will be seen that the driving mechanism for the endless conveyor 58 gets its power from a single source. Disposed within the feeding conveyor 2 are longitudinally disposed spaced slats 65 over which the transversely disposed bars 66 carried by the endless conveyor 58 ride for feeding and conveying potatoes upwardly and discharging the same onto the assorting table. By providing the spaced bars 65 it will be seen that potatoes below a predetermined size will drop between said bars into a discharge chute 67 disposed within the endless conveyor 58, and will discharge said undersize potatoes to one side of the feeding mechanism. Rockably mounted in bearings of the ends of the bars 57 is a transversely disposed shaft 68, which shaft is provided with a plurality of downwardly and inwardly extending arms 69 which normally engage on the adjacent ends of the spaced bars 65 and form a hopper into which potatoes are placed when feeding the device. It will be noted the bars 65 are closer together in the hopper portion of the feeding device, and as the bars 66 pass under the arms 69, there will be a partial agitating or shaking of the potatoes for dislodging dirt, which will not drop into the discharge hopper 67, consequently the undersize potatoes will be discharged substantially free of dirt. Where it is not desired to use a feeding mechanism as shown, the potatoes may be placed on the end of the assorting table, and the feeding conveyor eliminated, and at the same time the rock shaft 68 having the arms 69 may be attached to the end of the assorting table.

From the above it will be seen that an assorting table and feeding mechanism therefor is provided which is simple in construction, one wherein a continuous operation takes place, and one wherein the potatoes or other articles will be sized and can be easily assorted into different receptacles. It will also be seen

that the end of the assorting table is provided with spaced bag holders, and the hinged deflecting members which are linked together may be easily and quickly manipulated whereby potatoes may be discharged into bags carried by either bag holder. It is to be understood the frame and other parts of the device may be formed from any kind of material, wood, iron or otherwise, however it is preferably made from metal and built up from

10 angle iron.

The invention having been set forth what is claimed as new and useful is:—

1. The combination with a conveyor, of hinged deflecting members laterally movable above said conveyor, a link connection between said hinged members, a horizontally disposed guide bar above the conveyor, brackets carried by the hinged members and slidably mounted on the guide bar and arching the upper side thereof, said hinged members forming means whereby articles may be discharged into either of two bag holders, and means carried by the guide bar and cooperating with the brackets for holding the deflecting members in position to discharge into either of said bag holders.

2. The combination with a conveyor, of hinged deflecting members above said conveyor, supporting and guiding means for said deflecting members, said deflecting members being linked together, said supporting and guide means comprising a transversely disposed guide bar above the conveyor, U-shaped brackets carried by the deflecting members and arching the bar and supporting the deflecting members and latching means carried by the guide bar and positioned whereby when the free ends of the deflecting members are in extreme positions to either side of the conveyor, said U-shaped brackets will be gripped and held.

In testimony whereof I hereunto affix my signature.

E. LUSTER A. MORROW.
